ABSTRACT OF THE DISCLOSURE

A rope soap consisting of a bar of soap having at least one loose loop of rope extended from one side thereof. The bar defines a plurality of interconnected rope-accommodating grooves in which the loose rope is wound about the bar to form an integrally packaged unit therewith. The depths of the grooves may be chosen to form protective belts about the bar. Soap and rope of contrasting colors and/or complementing textures may be chosen to enhance the appearance of the integrally packaged unit.

BACKGROUND OF THE INVENTION

Field of the invention

This invention generally relates to soap and like solid cleansing devices and, more particularly, to a bar of soap with a rope which is wrappable about the bar to form an integrally packaged unit therewith.

Description of the prior art

Various combinations of bars or cakes of soap with strings attached to them are presently known. Basically, a string or rope has a portion embedded in the bar to form one or more loops which extend therefrom. These loops are used to suspend the bar at an accessible position while in use, or use them as handles to apply the bar to an otherwise less accessible part of a body, such as a bather's back. Such bars of soap, often referred to as "rope soap," are becoming increasingly popular with the competition for the consumer market increasing in direct proportion.

Though the various presently known rope soaps, now available, fulfill their intended functions, they are characterized by a common disadvantage which relates particularly to their handling and packaging, as well as affects the rope soap as a display item before the soap is sold to the consumer. Though the bars of soap have been designed in various shapes to produce aesthetic effects, the ropes extending therefrom generally spoil such effect because they extend from the bars as unrelated appendages.

Generally, the extending ropes are twisted up to hang as unattractive disorganized appendages which spoil the effect of the bars when displayed. Also, the size of the box or container in which the bar is placed must be increased to accommodate the twisted rope, as well as extraneous elements, about which the rope is wrapped or to which it is anchored. The rope, as well as the bar of soap tend to soil which affects the product's marketability. Furthermore, it has been found that bars of soap are often damaged or scraped during packing and shipment not only by the knotted ropes in their respective containers or wrappings, but by the extraneous elements as well.

OBJECTS AND SUMMARY OF THE INVENTION

Accordingly, it is a primary object of the present invention to provide a new improved rope soap which overcomes the disadvantage of prior art rope soaps.

Another object of the invention is to provide a rope soap in which the bar of soap and the rope extending therefrom, form an integrally packaged unit.

2

Yet another object is the provision of a rope soap which is packagable in a container or the like, the dimensions of which are limited by the dimensions of the bar of soap.

Still a further object of the invention is to provide a new rope soap in which the rope is packaged so as to protect the bar of soap to which it is attached from soiling or damage during packaging, display and shipment.

Yet a further object of this invention is to provide a new method of fabricating a rope soap, in which the rope is packagable to protect the soap and form an integral unit therewith.

These and other objects of the invention are achieved by providing a loop of rope extending from a bar of soap, which is provided with a plurality of interconnected grooves about selected sides thereof. The basic function of these grooves is to accommodate the loose part of the rope extending from the bar of soap, so that rather than tie the loose rope as an appendage of the bar of soap, the rope is wrapped around the bar within the grooves to form an integrally packaged unit therewith.

The number and locations of the grooves about the bar depend on the size and shape of the bar, as well as on the number of loose rope loops which extend from the

25 bar and the desired overall appearance of the bar with rope wrapped about it. However, irrespective of the specific groove combination, it is significant that each bar define grooves or channels so that the loose rope could be wrapped tightly around it to form a unitary element. 30 The grooves may be controlled to be sufficiently deep so that the rope therein does not extend about the outer bar surface. However, if desired, shallower grooves may be employed so that when the rope is wrapped therein, portions of the rope form protective belts about selected 35 sides of the bar. Such belts are useful in protecting the bar from being accidentally dented or otherwise damaged.

The novel features that are considered characteristic of this invention, are set forth with particularity in the 40 appended claims. The invention will best be understood from the following description, when read in connection with the accompanying drawings.

BRIEF DESCRIPTION OF THE DRAWINGS

45 FIG. 1 is an isometric view of an exemplary embodiment of the invention;

FIG. 2 is an isometric view of the embodiment shown in FIG. 1, in which the rope and bar form an integrally packaged unit;

50 FIG. 3 is a cross-sectional view along lines 3—3 of FIG. 2; and

FIG. 4 is an isometric view of another embodiment of the invention.

DESCRIPTION OF THE PREFERRED EMBODIMENTS

Reference is now made to FIG. 1, which is an isometric view of an embodiment of the invention exemplary of the teachings thereof. There is shown a rope soap 10 consisting of a bar of soap 12 in which the ends of a rope 14 are embedded with the rest of the rope extending through side 16 of the bar to form a loose loop 18. The loop is made sufficiently large to be looped over a fixture or a limb of the soap user, so that the soap is suspended at a convenient location while in use. Bar 12 which has a cross-sectional configuration, best described as arcuate or kidney-shaped, defines a concave groove 20 which extends along the backside of the bar from end 16 to an opposite end 22. The bar defines a second relatively wide groove 24, which encircles the bar preferably near end 22. Groove 24 opens into or is in communication with groove 20 at the backside of the bar of soap.

As previously generally indicated, the function of these grooves is to accommodate the loose rope 14, forming loop 18, during handling display and shipping, so that the soap and the rope form an integrally packaged unit. FIG. 2 represents such a unit for the particular rope soap 10, shown in FIG. 1. As may be seen from FIG. 2, the rope is not packaged as a separate knotted appendage, but rather is wrapped around portions of the bar 10 within grooves 20 and 24.

To achieve the wrapping arrangement, shown in FIG. 2, the loose rope 14 is pulled downwardly along groove 20 with one side of the loop wrapped around the bar within groove 24. At the point of intersection of the two grooves at the back of the bar, the remaining portion of the rope may be pulled under the rope convolutions in groove 24 and thereafter placed in the section of groove 20 between the point of intersection of the two grooves and end 22. If desired, a decorative pin may be used at the point of intersection to secure the end of the rope to the bar with the rest of the rope snugly held within the grooves.

The entire unit may be protected from soiling by inserting it into a suitable transparent plastic cover 28 (FIG. 2), shaped to accommodate the bar and rope therein. Preferably, the depth of groove 24 is controlled with respect to the rope cross-section, so that the outer surfaces of the rope convolutions in groove 24 extend above the front surface of the bar. These rope surfaces provide sufficient friction to the cover to securely maintain it in place, until the cover is deliberately removed.

FIG. 3 is a cross-sectional view of the arrangement shown in FIG. 2 along lines 3—3 with the cover 28 over the integrally packaged unit.

The depths of the grooves may be controlled to be deep enough relative to the rope thickness so that the rope is completely accommodated therein. Alternatively, some or all of the grooves may be shallower than the rope thickness so that portions thereof extend above the outer bar surface, forming a protective band thereabout. Such an arrangement may be most useful to protect some or all of the sides of the bar of soap from being dented during shipment.

FIG. 4 to which reference is made herein, is an isometric view of such a unit. In FIG. 4, elements like those previously described are designated by like numerals. As may be seen from FIG. 4, the rope 14 encircles the bar 12 about its periphery 12, forming a protective ring thereabout, as well as protecting the front and back faces by the pair of rope convolutions wrapped around the two faces. Though such a unit may be deemed sufficiently protected, if desired it may be covered by a plastic cover, held in place by the friction between its inner surface and the protruding rope. To further enhance the marketability of the unit, the rope and bar may be of different colors and/or texture to produce a highly pleasing product.

There has accordingly been shown and described herein a novel rope soap. It includes a bar of soap which defines a plurality of grooves accommodating the loose portion of the rope extending from the bar, and thereby results in an integrally packaged unit. It should be appreciated that differently sized and shaped bars may be used. The bars may be of soap or any similar solid soluble cleanser. Also, the number and locations of the grooves on the bar are subject to choice. The only basic requirement being that the grooves be so arranged and interconnected that the loose rope can be conveniently and easily wrapped around the bar and tightly accommodated within the grooves to integrate with the bar of soap.

It is appreciated that those familiar with the art may make modifications and/or substitute equivalents without the arrangements as shown without departing from the spirit of the invention. Therefore, all such modifications and/or equivalents are deemed to fall within the scope of the invention as claimed in the appended claims.

What is claimed is:

1. A rope soap consisting essentially of:
a bar of solid soluble soap; and
a rope having its ends embedded in said bar of soap
to form a rope loop extending from said bar at one
end thereof, said loop being substantially longer
than the largest circumference of said bar and long
enough to accommodate a limb of the bar user
therein, said bar defining a plurality of rope-accom-
modating grooves in selected sides thereof, with sub-
stantially all the rope extending from said bar being
woundable in said grooves to form an integral unit
with said bar during shipment and display, with the
size of said unit being substantially equal to the
size of said bar of soap.

2. The device as recited in claim 1 wherein the depth
of some of said grooves is less than the thickness of said
rope whereby when said rope is accommodated in said
grooves at least a portion thereof extends therefrom to
form a protective surface about said bar.

3. The device as recited in claim 1 wherein said bar
comprises a bar of soap with front and back sides and
defining interconnected rope-accommodating grooves, at
least one circumferential groove extending around the
body of said bar, whereby said rope when wound about
the bar and accommodated in said circumferential
groove, defines at least one rope belt around said bar,
and another of said grooves extending substantially the
full length of said bar along its back side for accommo-
dating a portion of the rope extending from said one
end and the rest of the rope which is not wound in said
at least one groove.

4. The device as recited in claim 4 further including a
plastic cover snugly covering said bar and the rope
wrapped thereabout with the depth of some of said
grooves being less than the rope thickness so that a
portion of the rope extends beyond the bar surface to
frictionally engage said plastic cover to inhibit its acci-
dental removal from said bar.

5. The device as recited in claim 1 wherein said bar
comprises a bar of soap with front and back sides parallel
to a longitudinal axis which is perpendicular to said one
end, said bar defining a continuous groove about the
entire periphery thereof between said front and back
sides, said continuous groove being shallow with respect
to the rope thickness whereby the rope in said continuous
groove extends beyond the bar surface to form a pro-
tective belt about the bar of soap.

6. The device as recited in claim 5 further including
a plastic cover snugly covering said bar and the rope
wrapped thereabout with the rope which extends beyond
the bar surface frictionally engaging said plastic cover
to inhibit its accidental removal.

7. The method of fabricating a rope soap the steps
consisting essentially of:
forming a bar of soap of a selected shape with only
the ends of a rope embedded in said bar, the rope
extending from one side thereof to form a loose rope
loop, which is longer than the largest bar circum-
ference and which is sufficiently long to accommo-
date a part of a user body therein, said bar being
formed with rope-accommodating grooves extend-
ing about selected sides thereof; and
wrapping the loose rope in said grooves about said bar
to form a unit therewith for shipping and display
purposes, the size of the unit being substantially
equal to the size of said bar.

8. The method as recited in claim 7 wherein some of
said grooves are shallower than the rope cross-section,
whereby the rope, when wound about the bar, forms at
least one protecting belt thereabout to protect the bar
surface during shipment and display.
